UNITED STATES PATENT OFFICE

150,743

DESIGN FOR A SHOE

Adolph Wertheim, New York, N. Y., assignor to
Setry Inc., New York, N. Y.

Application May 10, 1948, Serial No. 146,265

Term of patent 3½ years

(CL. D7—7)

To all whom it may concern:

Be it known that I, Adolph Wertheim, a citizen of the United States, residing at New York city, in the county of Kings and State of New York, have invented a new, original, and ornamental Design for a Shoe, of which the following is a specification, reference being had to the accompanying drawing, forming a part thereof.

Fig. 1 is a side elevational view of a shoe, showing my new design.

Fig. 2 is a top plan view thereof.

Fig. 3 is a side elevational view of the shoe, showing the side opposite to that shown in Fig. 1.

Fig. 4 is a front elevational view of the shoe.

I claim:

The ornamental design for a shoe, substantially as shown.

ADOLPH WERTHEIM.
